UNITED STATES PATENT OFFICE.

MILON JOSEPH DEMOREST, OF BELDING, MICHIGAN.

MOLD FOR CONCRETE WALLS.

No. 868,764.

Specification of Letters Patent.

Patented Oct. 22, 1907.

Application filed March 11, 1907. Serial No. 361,792.

To all whom it may concern:

Be it known that I, MILON JOSEPH DEMOREST, a citizen of the United States of America, residing at Belding, in the county of Ionia and State of Michigan, have 5 invented certain new and useful Improvements in Molds for Concrete Walls; and I do hereby declare the following to be a full, clear, and exact description of the invention, such as will enable others skilled in the art to which it appertains to make and use the same. 10 My invention relates to improvements in molds for concrete walls, and its object is to provide a convenient device for forming walls wholly of concrete, and also adapted to forming a thin concrete coating having the appearance of a concrete wall, upon the surface of 15 an ordinary wooden building, and to provide the device with various new and useful features hereinafter more fully described and particularly pointed out in the claims.

My device consists essentially of a mold wall made 20 preferably of sheet metal and reinforced with angle bars, this wall being made in short sections connected by means of rods extending vertically through the overlapping ends of the angle bars, whereby the device may be adapted to buildings of various sizes; supporting 25 bars by which this wall is held in place when in use, bolts by which these supporting bars may be connected either to an inner mold wall for forming walls entirely of concrete, or attached to the outer surface of 30 an ordinary wooden building, whereby said surface may be coated with concrete molded on the outer surface to imitate a concrete wall, as occasion may require, and a core adapted for use when forming hollow walls, and in various features of combination and arrangement, as will more fully appear by reference to 35 the accompanying drawings, in which:

Figure 1. is a perspective of my device arranged to operate in conjunction with an inner mold wall for forming walls wholly of concrete; Fig. 2. a transverse section of the same; Fig. 3. an elevation of the core for 40 forming a hollow wall; Fig. 4. an inverted plan view of the same; Fig. 5. a perspective illustrating the arrangement of my device for coating the outer surface of an ordinary wooden building; and, Fig. 6. a transverse section of the same.

Like numbers refer to like parts in all of the figures. 45 1 represents the wall of a mold which wall is preferably made of stamped sheet metal to form the concrete to represent any preferred kind of work in brick or stone, the form shown being a plain, flat wall with pointed 50 seams. This mold wall is preferably reinforced by means of angle bars 3 extending longitudinally of its outer surface and secured thereto, and is made in short sections with the angle bars prolonged beyond the ends of the sections and overlapped as at 4 and the sections 55 secured end to end by means of rods 5 extending vertically through openings in the overlapped portions of

the angle bars. One section of this wall is made angular to extend around the corner of a building and for the purpose of using this mold to form walls wholly of concrete, an inner wall 2 of any convenient material and 60 construction may be used and the wall 1 is secured in place and spaced apart from the other wall by means of supporting bars 7 and 8 connected above and below the outer wall by bolts 9 whereby they are held against the pressure of the material therebetween and adjusted for 65 thickness of the concrete, the lower bolts 9 extend through the upper portion of the part of the wall last formed and support the mold thereon as indicated in Fig. 2.

To form a chamber in the interior of the wall, I provide a core consisting of two vertically corrugated sheets of metal 10 connected at their upper edges to a bar 11, one of which sheets is pivotally connected to the bar and the other rigidly connected to the same, whereby their lower edges will move toward and from each 75 other. To sustain these plates in parallel planes, I provide them near their lower edges with reinforcing angle bars 12 and 13, and to adjust the same and permit of movement toward each other, rods 14 are journaled in the bar 11 and the angle bar 13 and each provided 80 with a crank member 16 at its lower end, which engages the bar 12, and also provided with an eye 15, by which the rod is manually rotated. When the cranks 16 are adjusted to hold the lower edges of the plates 10 apart, the plates will be in parallel planes and when the rods 85 14 are manually rotated with the crank 16 turned away from the bar 12, the plates will approach each other at the lower edge, and can then be readily removed upward from between the respective sides of the concrete wall. This core can then be vertically adjusted and 90 again separated at the bottom by turning the rods when the friction of their lower portions against the concrete will sustain them in place while forming the next layer of the wall.

For coating an ordinary wooden building on the outside with a thin cement structure molded in imitation of stone work, or otherwise the wall 1 is supported at any desired distance from the surface of the building by means of shorter bolts or lag screws 9^a in place of the bolts 9, these bolts or screws being inserted in the 95 wall of the wood building which takes the place of the inner wall 2. To more securely retain this thin layer of concrete in place, I prefer to apply to the building a wire netting 19 secured thereto by nails or staples. However, this is not necessary; lath, nails or other suitable means of attachment may be used. Obviously 100 these molds are moved upward step by step as the work progresses, and the holes in the concrete formed by the bolts or lag screws are filled up.

What I claim is:

1. In a mold for concrete walls, a mold wall comprising a series of sections consisting of stamped sheet metal and

110

105

2
angle bars attached thereto the corner sections being bent in angular form, and the sections secured to each other by rods extending vertically through the overlapped ends of all of the angle bars, an inner mold-wall, vertically disposed supporting bars engaging the angle bars, and bolts connecting the said bars and the inner wall, and also extending above and below said mold-walls.

2. In a mold for hollow concrete walls, a core comprising two corrugated sheet metal plates, a bar to which said plates are attached one of said plates being movable toward and from the other plate at the lower edge, sup-

porting bars attached to the respective plates near the lower edges, a rod journaled in the upper bar and in one of the lower bars, a crank member on the rod and engaging the other lower bar to space the plates apart at their lower edges, and means for manually rotating the rod. 15

In testimony whereof I affix my signature in presence of two witnesses.

MILON JOSEPH DEMOREST.
